CLAIM

The ornamental design for a battery connector, as shown and described.

DESCRIPTION

FIG. 1 is a perspective view of a battery connector, according to an embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The jagged broken lines on the barrel of the battery connector represent a symbolic break in length. The appearance of any portion of the article between the break lines forms no part of the claimed design. The remaining broken lines illustrate portions of the battery connector and environmental structure that form no part of the claimed design.
